GAME BOARD

Charles C. Travis, 50 College NE., Apt. 1,
Grand Rapids, Mich. 49503

Filed May 8, 1968, Ser. No. 11,840

Term of patent 14 years

Int. Cl. D21—01

U.C. Cl. D34—5

FIG. 1 is a plan view of the novel game board;
FIG. 2 is a cross-sectional view taken along plane II—II
of FIG. 1;

FIG. 3 is a side-elevational view thereof; and
FIG. 4 is an end-elevational view thereof.
The hemispherical projections are an integral part of
the board.

I claim:

The ornamental design for a game board, substantially
as shown and described.
